UNITED STATES PATENT OFFICE.

ELIZABETH H. NATSCH, OF NEW YORK, N. Y.

GARBAGE-HOLDER.

1,167,920.

Specification of Letters Patent. Patented Jan. 11, 1916.

Application filed April 12, 1915. Serial No. 20,687.

To all whom it may concern:

Be it known that I, ELIZABETH H. NATSCH, a citizen of the United States, and a resident of the borough of Brooklyn, county of Kings,

5 city and State of New York, have invented certain new and useful Improvements in Garbage-Holders, of which the following is a specification.

My invention relates particularly to the 10 cans or receptacles used for the temporary storage of garbage and refuse until collected for final disposal, and is designed to afford simple, cheap, but convenient and effective, means whereby the cover of the receptacle 15 may be quickly and easily removed or applied, while at the same time provision is made for securely holding the cover in position on the receptacle without danger of accidental displacement.

20 I am aware that various locks and devices, more or less complicated, have been proposed for the purpose, which lack the simplicity and cheapness of structure which seems indispensable to practical and commercial utility and success,—whereas by my 25 construction and arrangement of parts the receptacle and cover remain essentially the same as heretofore, and the labor involved in attaching or detaching the cover is practically the same, or little greater or more difficult than where no fastenings are provided. At the same time I attain ample protection 30 against accidental displacement of the cover as hereinafter more fully set forth,—the invention consisting in the specific construction, combination, and arrangement of parts 35 described and claimed, distinguishing features being an inturned bead at the mouth of the receptacle, and a plurality of elastic re-

40 silent clips for engagement therewith positioned on the under side of the cover, which latter is also formed with a cylindrical flange fitting externally and snugly over the annual mouth of the receptacle, thereby acting 45 as a guide to centralize and aline the said spring clips with relation to said inturned bead, so that the cover may be quickly and conveniently applied, positioned upon, and secured to, the receptacle to effectually 50 seal the latter without the exercise of special skill or care by the applier.

In the accompanying drawings, Figure 1, is a view of the under side of the cover of my improved garbage receptacle; Fig. 2, is 55 a central vertical sectional elevation of the receptacle with the cover in place; Fig. 3,

an enlarged sectional detail of one of the clip fastenings; Fig. 4, shows possible modifications of the retaining bead in sectional detail.

60 The main portion of my improved garbage holder consists of the receptacle R, which is of course preferably cylindrical in shape, although not necessarily so, and of suitable depth and width. In fact it differs mainly 65 from the ordinary garbage can in having an inturned bead r, formed at or approximately at, its mouth edge. This bead r, may or may not be reinforced by a wire filling, as may be found most expedient; and it is preferably 70 an annular bead, as shown in Figs. 2, and 3, extending all around the mouth of the receptacle, although I do not limit myself to an annular flange because segmental beads may be substituted with like results if positioned 75 on the receptacle to engage with the series of clip fastenings c, on the under side of the cover C. Neither do I limit myself to a bead circular in cross section, as modifications thereof may be resorted to as in Fig. 4,—the 80 essential feature in this respect being an in-turned shoulder for engagement with the spring clips c, on the cover.

85 Any plural number of clip fastenings c, may be provided on the inside of the cover, preferably three positioned equidistant with relation to each other, as shown in Fig. 1. They may be made of spring metal or any other elastic resilient material, with shanks c', adapted to be riveted or otherwise secured to the under side of the cover C, and with their free ends bent to form clasp contacts c², for engagement with the retaining bead r, over which said curved ends c², of the spring c, ride when the cover is forced upon 90 or from the receptacle. The cover C, is formed with the deep external flange c³, fitting snugly over the mouth and upper portion of the receptacle R, as shown. This externally fitting cover flange c³, performs a 95 double function in that it not only effectually seals the receptacle when properly positioned thereon but also acts as a centralizing guide to aline the spring clips accurately and simultaneously with relation to the in-turned retaining bead r, so as to facilitate the coupling of the parts and insure a perfect closure without the exercise of special 100 care or skill in the operation. For a like reason, by effecting the perfect alinement of parts, it facilitates the removal of the cover 105 when the latter is pulled up centrally by

means of the handle c^3 . It is to be noted in this connection that the only operative parts, if the spring clips c , may be designated as such, are upon the inside of the cover, where 5 they afford no obstruction, and are out of contact with the contents of the can R ; and when the cover is removed the can is left free and unobstructed for the dumping of its contents.

10 Thus for all practical purposes my improved garbage receptacle is as plain and simple as the ordinary sheet metal garbage can in which the cover is presumably held in position on the can by frictional contact 15 alone. But unfortunately this frictional contact is not always sufficient to retain the lid in position should the can be overturned, subjected to invasion by dogs or cats, rough usage, or accidental contact with extraneous 20 objects, &c., whereas my method of interlocking affords sufficient resistance to retain the cover in position under such circumstances, while at the same time a comparatively slight push or pull applied centrally 25 to the cover through the medium of its handle c^3 , is sufficient to overcome the resistance afforded by the elastic resilient spring clips c , so that the cover C , may be intentionally removed or replaced with comparative 30 ease.

For sanitary reasons it is obvious that flies should be excluded from the can, and its contents protected against exposure or overflow until collected for final disposal; 35 and also that the means for attaining these results should be isolated and protected from contact with extraneous objects, all of which I attain by my construction and arrangement of parts at an expense little if any 40 above the cost of the ordinary plain garbage can, which externally my improved garbage receptacle resembles in appearance. Furthermore this isolation and protection of the fastening means is an important factor in 45 the life and utility of the receptacle, and is rendered possible by the simple but effective expedient of the inturned retaining bead r , and there are no complicated parts to get out of order and thereby render the device 50 inoperative and useless. The receptacle R , may be provided with the usual pail handle r' , or equivalent means to facilitate carriage or manipulation.

It is to be understood that by the use of 55 the term "inturned retaining bead" I here-

in mean to designate any inturned form of retaining shoulder adapted for engagement with elastic resilient clips substantially as herein set forth.

What I claim as my invention and desire 60 to secure by Letters Patent is,

1. In a garbage holder of the character designated, the combination of a receptacle formed at its upper end with an inturned bead, and a cover having a depending external flange to embrace the upper portion 65 of the receptacle, and with spring members following the contour of and secured to the under side of the cover and having each a curved terminal adapted to spring under 70 said bead when the cover is forced down upon the receptacle for the purpose described.

2. In a garbage holder of the character designated, the combination of a receptacle 75 formed with an inturned retaining bead and an externally flanged cover formed with a plurality of elastic resilient clips adapted to engage with said retaining bead, for the purpose described.

3. A garbage holder of the character designated, comprising a cylindrical receptacle the mouth of which is formed with an annular inturned retaining bead, and a cover formed with a cylindrical flange fitting externally and snugly over the annular mouth of said receptacle, said cover being also formed on its under side with a plurality of equidistant elastic resilient clips adapted to engage with said inturned retaining bead 90 on the mouth of the receptacle, for the purpose set forth.

4. A garbage holder of the character designated, comprising a cylindrical receptacle the mouth of which is formed with an annular inturned retaining bead, and a cover formed with a cylindrical flange fitting externally and snugly over the annular mouth of said receptacle, said cover being also formed on its under side with a plurality of 95 equidistant elastic resilient clips each formed with a curved terminal adapted to spring under said retaining bead when the cover is forced down upon the receptacle, for the purpose set forth.

ELIZABETH H. NATSCH.
